(57) **CLAIM**

(52) **U.S. Cl.**

The ornamental design for a TAPERED ARTICULATING ARM ASSEMBLY FOR WALL-MOUNTED DISPLAY MOUNT as shown.

USPC **D8/380; D14/239**

DESCRIPTION

(58) **Field of Classification Search**

USPC D8/380; D14/239, 452; D8/380-381, 374, D8/355, 363, 373; D14/224, 434, 451-452, D14/371-374; D6/681
CPC F16M 11/2085; F16M 11/2092; F16M 11/2007; A47B 2097/005; A47B 2097/006; F16M 11/2014; F16M 11/2021; F16M 11/105; F16M 11/10; F16M 11/048; F16M 11/12; F16M 13/02; H05K 5/0004; H05K 5/0017; H05K 5/0217; H05K 5/02

FIG. 1 is a front isometric view of a TAPERED ARTICULATING ARM ASSEMBLY FOR WALL-MOUNTED DISPLAY MOUNT, showing the new design;
FIG. 2 is a front elevation view of the TAPERED ARTICULATING ARM ASSEMBLY FOR WALL-MOUNTED DISPLAY MOUNT depicted in FIG. 1;
FIG. 3 is a right elevation view of the TAPERED ARTICULATING ARM ASSEMBLY FOR WALL-MOUNTED DISPLAY MOUNT depicted in FIG. 1;
FIG. 4 is a left elevation view of the TAPERED ARTICULATING ARM ASSEMBLY FOR WALL-MOUNTED DISPLAY MOUNT depicted in FIG. 1;
FIG. 5 is a top plan view of the TAPERED ARTICULATING ARM ASSEMBLY FOR WALL-MOUNTED DISPLAY MOUNT depicted in FIG. 1; and

FIG. 6 is a bottom plan view of the TAPERED ARTICULATING ARM ASSEMBLY FOR WALL-MOUNTED DISPLAY MOUNT depicted in FIG. 1.
The broke lines in the drawings depict parts of the article that form no part of the claimed design.
